WILLIAM M. STEVENSON, OF SHARON, PENNSYLVANIA.

Letters Patent No. 83,336, dated October 20, 1868

IMPROVEMENT IN BALANCE SLIDE-VALVES.

The Schedule referred to in these Letters Patent and making part of the same.

To all whom it may concern:

Be it known that I, WILLIAM M. STEVENSON, of Sharon, in the county of Mercer, and State of Pennsylvania, have invented certain new and useful Improvements in Balance Steam-Cut-Off Valves; and I do hereby declare that the following is a full, clear, and exact description thereof, reference being had to the accompanying drawings, and to the letters of reference marked thereon, which form a part of this specification, in which is represented a longitudinal section of my invention.

The nature of my invention consists in an additional wall to the sides of a steam-valve, either on the outside or inside, these walls taking up the full width of the port-lap or flange that covers the ports.

In order to enable others skilled in the art to make and use my invention, I will now proceed to describe its construction and operation.

A represents the steam-chest, made in any of the known and usual ways.

a a are the two walls which cover the openings *CC* in the bottom of the steam-chest. Between these walls is a cavity, *d*, open both at top and bottom, which, as shown in the drawing, is smaller at the bottom by about one-half than at the top.

The walls are, at their tops, provided with grooves, in which I insert packing-strips *e e*. These strips are three-cornered, and under them steam is admitted,

through the holes *i i*, for the purpose of adjusting them to the cap of the steam-chest, thereby seating the valve, and allowing no steam to escape under or over the valve.

The cavity *d*, between the walls *a a*, is filled with steam when the same is let past the edge of the valve into the ports or cylinder. The object of this is to cause a downward pressure on the valve at the time there is an upward pressure, by steam, in the ports on the exposed part of the port-lap, thus making the steam counterbalance itself at the most critical points of the travel of the valve.

Having thus fully described my invention, What I claim as new, and desire to secure by Letters Patent, is—

A steam-valve, constructed as described, with a cavity, *d*, between the walls *a a*, and with packing-strips *e e*, in grooves on the top of the walls, steam being admitted through holes *i i*, under said strips, pressing them up against the cap of the steam-chest, substantially as and for the purposes herein set forth.

In testimony that I claim the foregoing as my own, I affix my signature in presence of two witnesses.

WM. M. STEVENSON.
